Primary Examiner — Cynthia Ramirez*Assistant Examiner* — Jeremy S. Swartz(74) Attorney, Agent, or Firm — ScienBiziP, P.C.(57) CLAIM

The ornamental design for a display box, as shown and described.

DESCRIPTION

FIG. 1 is a front, right and top perspective view of a display box in an open state, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1; and,

FIG. 10 is another front, right and top perspective view of the display box in a closed state.

The broken lines in the drawings depict portions of the display box that form no part of the claimed design. In addition, the dot-dash broken lines in the drawings illustrate an enlarged portion of the design.
